UNITED STATES PATENT OFFICE.

MARTHA E. BUSSLER, OF NEW ORLEANS, LOUISIANA.

DEHYDRATING APPARATUS.

Application filed January 4, 1928. Serial No. 244,459.

This invention relates to a dehydrating unit.

An object of the invention is the provision of a unit having a self contained curing compartment in close association with a drying compartment, with the compartments so associated that the greater portion of the heat will be directed into the curing compartment while a lesser portion will be applied to the articles in the drying compartment.

A further object of the invention is the provision of a dehydrating unit including a housing having a curing compartment in communication at the bottom thereof with the housing and a drying compartment located above the curing compartment and open to the air in the housing, an oscillating fan being employed for causing the hot air in the compartment to be forced in an alternate series through a plurality of trays forming the drying compartment.

This invention will be best understood from a consideration of the following detailed description in connection with the accompanying drawings; nevertheless, it is to be understood that the invention is not confined to the disclosure being susceptible of such changes and modifications as shall define no material departure from the salient features of the invention as expressed in the appended claims.

In the drawings:—

Figure 1 is a view in perspective with parts of the dehydrating unit broken away,

Figure 2 is a view in perspective with parts broken away showing the air conduit,

Figure 3 is a fragmentary view in elevation of the front of the dehydrating unit,

Figure 4 is a vertical section of the unit.

Figure 5 is a horizontal section taken along the line 5—5 of Fig. 4,

Figure 6 is a view in perspective of a clip supporting the outer free end of the air conduit.

Referring more particularly to the drawings 10 designates a housing having a door 11 hinged at 12 for closing the entrance to the housing. Keepers 13 are provided for maintaining the door closed. The top 14 of the housing is provided with a discharge conduit 15 for conducting the hot air and gases away from the interior of the housing, the bases being supplied by a burner 16 of any well known type. A pipe 17 is connected with an opening 18 in the rear

wall 19 of the housing for conducting hot air and gases from a curing chamber 20 formed in the lower portion of the housing. The upper portion of the housing, as shown at 21, forms a drying chamber. A baffle 22 is spaced from the top 14 of the housing and terminates at 23 adjacent the rear wall 19 so that warm air is discharged from the chamber 21 at the rear upper end of said chamber before it reaches the discharge pipe 15.

The curing chamber is formed by a housing 24 which has its lower end open to the housing while side walls 25, front end wall 26 and rear wall 27, which constitutes part of the rear wall 19 of the housing 10, and a top 28 all cooperate to provide a curing chamber. A plurality of trays 29, 30 and 31 are located in spaced parallel relation within the housing 24 and are adapted to receive the products to be cured. Side flanges 32 aid in maintaining the articles on said trays. These trays abut the rear wall 19 of the housing 10 and are spaced from the front end wall 26 to provide a passage 33 for the hot air. The trays 29 to 31 inclusive, are tilted at an angle to the horizontal so that their inner ends are at a lower level than the rear ends. A door 34 provides a closure for an opening 35 in the front end 26 of the housing 24.

A pipe 40 has an open end 41 terminating at the front of the housing 10 and supported at said end by a clip 42 secured to the bottom of said housing and below the door 11. The rear end is secured to the bottom 43 of the housing 10 and has a port 44 leading into the curing chamber 20. A baffle plate 45 is tilted at an angle to the horizontal and supported by the side walls 46 of the housing 10 and terminates adjacent the lower end of the front portion 26 of the housing 24. The heater 16 is located below the baffle plate 45 and the hot air from said heater is directed by the baffle into the lower open end of the curing chamber.

A plurality of trays 50 are arranged in spaced relation within the drying chamber 21 and are supported by vertically disposed bars 51 secured to the side walls 46 of the housing 10. These trays have their forward ends at a lower level than the rear ends and are adapted to support articles to be dried. Flanges 52 are secured to the side edges of the trays to prevent the materials from being discharged from the trays. It is to be

noted that the trays beginning with the second tray 50^a which is directly below the uppermost tray 50, and all of the succeeding trays are progressively spaced from the door 11 by a greater distance, thereby providing a greater space between the front ends of the lowermost trays and the door 11 than the upper trays. The rear end of the uppermost trays are spaced a greater distance from the rear wall 19 than the lowermost trays.

An oscillating fan 60 is driven by an electric motor 61, secured to the door 11, and is adapted to force the hot air continuously through the spaces between the trays 50, 50^a and 50^b towards the rear wall 19 of the housing 10. Since this fan is of the oscillating type the air will be forced through either of the lower or uppermost trays initially after which the air is progressively forced through the other trays until the fan reverses its position when the reverse supply of air is had. By this construction the air is maintained in a constant state of agitation and all the trays are equally supplied with a predetermined quantity of hot air.

By opening the door 34 more air is forced through the front end of the housing 24 and thus through the trays 29 to 31 inclusive. The greater portion of this air, however, is forced through the curing chamber and out through the discharge pipe 17. The remaining portion of the air which is supplied by the conduit 40 is driven by the fan 60 through the trays in the drying chamber 21 after which said air is discharged past the rear end 23 of the baffle 22, and out through the discharge pipe 15. A screen 62 is mounted in the pipe 40 and aids in removing foreign matter from the air before it is received within the curing chamber 20.

I claim:—

1. A dehydrating apparatus comprising a housing, a curing compartment in the bottom of the housing, a drying compartment above the curing compartment, a burner in the housing, a baffle associated with the burner for directing hot gases from the burner to the curing compartment and also to the drying compartment, and means for supplying a tempering air to the curing compartment, so that the temperature of the curing compartment will be lower than the temperature of the drying compartment.

2. A dehydrating apparatus comprising a housing, a curing compartment in the bottom of the housing, a drying compartment above the curing compartment, a burner in the housing, a baffle associated with the burner for directing hot gases from the burn-

er to the curing compartment and also to the drying compartment, means for supplying air to the bottom of the housing, and directly to the curing compartment, and means associated with the drying compartment for forcing a portion of the heated air through said compartment.

3. A dehydrating apparatus comprising a housing, a curing compartment in the bottom of the housing, a drying compartment above the curing compartment, a burner in the housing, a baffle associated with the burner for directing the hot gases from the burner to the curing compartment, and also the drying compartment, means for supplying air to the bottom of the housing, said curing compartment having the lower end open to the housing and air.

4. A dehydrating apparatus comprising a housing, a curing compartment in the bottom of the housing, a drying compartment above the curing compartment, a burner in the housing, a baffle associated with the burner for directing hot gases from the burner to the curing compartment and also to the drying compartment, means for supplying air to the bottom of the housing, the curing compartment having an opening at the inner end for admission of hot air and a door for controlling the admission of air.

5. A dehydrating apparatus comprising a housing, a curing compartment in the bottom of the housing, a drying compartment above the curing compartment, a burner in the housing, a baffle associated with the burner for directing hot gases from the burner to the curing compartment, and also to the drying compartment, means for supplying a tempering air to the curing compartment, a plurality of trays, and means providing for a uniform distribution of hot air to the trays.

6. A dehydrating apparatus comprising a housing, a curing compartment in the bottom of the housing, a drying compartment above the curing compartment, a burner in the housing, a baffle associated with the burner for directing hot gases from the burner to the curing compartment, and also to the drying compartment, a plurality of trays in the drying compartment, means for supplying air to the bottom of the housing, a curing compartment having the lower end open to the air supply, and means for uniformly and successively distributing hot air to the trays.

Signed at New Orleans in the parish of Orleans and State of Louisiana this 29th day of December, A. D. 1927.

MARTHA E. BUSSLER.
